MARINE TURBINE.

1,155,516.

Specification of Letters Patent.

Patented Oct. 5, 1915.

Application filed September 12, 1913. Serial No. 789,463.

To all whom it may concern:

Be it known that I, HENRY F. SCHMIDT, a citizen of the United States, and a resident of Pittsburgh, in the county of Allegheny and State of Pennsylvania, have made a new and useful Invention in Marine Turbines, of which the following is a specification.

This invention relates to turbines and has for an object to produce a turbine, or combination of turbines, which is well adapted to be employed in marine propulsion.

A further object is to produce a highly efficient marine turbine which operates at low or cruising speeds with high, and better economy than other turbines known to me.

A further object is to produce a marine turbine, or organized turbine apparatus, which is lighter, in proportion to its capacity, and occupies less space than other turbines known to me.

A further object is to produce an organized apparatus for marine propulsion comprising separate coöperating turbines, so constructed and arranged that substantially full speed may be developed even though one of the turbines, included in the organized apparatus, is incapacitated.

These and other objects I attain by means of a turbine, or organized turbine apparatus, embodying the features herein described and illustrated in the drawings accompanying and forming a part of this application.

In the drawings, Figure 1 is a diagrammatic sectional view of a turbine embodying my invention and shown in connection with a conventional plan view of a reduction or transmission gearing, which may be employed between the turbine and the apparatus to be driven thereby. Fig. 2 is a sectional view along the line 2—2 of Fig. 1 and illustrates an arrangement of nozzles, which may be employed in one of the turbines, or turbine stages, forming a part of my invention. Fig. 3 is a diagrammatic sectional view of a turbine, or organized turbine apparatus, which forms an embodiment of my invention.

Referring to the drawings, and particularly to Fig. 1, the apparatus illustrated, as an embodiment of my invention, may be termed a triple flow turbine, since the motive fluid after having traversed a working

stage or a portion of the working passage 55 of the turbine, is divided into three streams and is caused to pass through a divided flow low pressure section including three separate paths. In the illustrated embodiment of the invention, the motive fluid is first 60 partially expanded and the velocity energy, rendered available by the partial expansion, is abstracted by impulse blades, which may be termed the blades of the initial stage 65 of the turbine. The expanded fluid, after being discharged from the initial stage, is 70 divided into three streams and is delivered to three reaction sections, two of which are shown as comprising a separate turbine, or turbine section. It will be apparent that 75 the motive fluid may be partially expanded, a greater or less amount, in the initial stage and that additional sets of expansion nozzles and additional rows of blades may be employed in the initial stage. It will also 80 be apparent that my invention contemplates a turbine in which the low pressure sections are impulse instead of reaction sections, or a turbine in which any combinations of the different types of turbine sections may be 85 employed.

As illustrated in Fig. 1, the turbine, or organized turbine or turbine element apparatus, consists of a turbine 10, comprising a rotor 4 and its inclosing casing 5, and a 85 turbine or turbine element 10^a, comprising a rotor 6 and its inclosing casing 7. While the turbine 10^a is, in effect, a low pressure turbine, the turbine 10 cannot be accurately termed a high pressure turbine, although 90 high pressure motive fluid is delivered to it, and a portion of the fluid is then after having been partially expanded, delivered to the turbine 10^a during the development of full power by the organized turbine apparatus. 95 The turbine 10 is equipped with a low pressure section which is operative during the entire operation of the organized turbine, and while the turbine 10 is operating alone as a cruising turbine. While the low pressure section of the turbine 10 is adapted to expand motive fluid to exhaust or condenser pressure, it is not of sufficient size to pass all 100 of the motive fluid delivered to the initial stage of the turbine when the organized apparatus is running at full speed or is developing full power. The motive fluid is therefore divided, prior to being delivered

to the low pressure section of the turbine 10, and a portion of the motive fluid is delivered to the turbine 10^a.

Throughout the further description of my invention I have considered the embodiment of it as consisting of three turbine elements operating as an organized apparatus, but it will be clearly apparent, to those acquainted with the nomenclature of the turbine art, that the embodiment of the invention illustrated would more accurately be described as a single turbine divided into two sections and provided with a reversing stage, since neither of the turbine elements 10 nor 10^a is in reality a complete turbine capable of efficiently developing full power without the coöperation of the other.

The turbine 10, as illustrated, is provided with an inlet port 11, which communicates with a source of high pressure motive fluid and is adapted to deliver motive fluid to one or more expansion nozzles 12. The nozzles 12 may be, and preferably are adapted to partially expand the motive fluid passing through them and to deliver it to impulse blades 13, mounted on a wheel 14 forming a part of the rotor 4. Two rows of blades 13 are shown mounted on the wheel, but it will be understood that the energy, rendered available by the expansion of the motive fluid, may be abstracted by any desired number of rows of blades. In the turbine illustrated the nozzles 12 and blades 13 constitute, what may be termed, a variable or partial admission, initial or primary section of the turbine and the motive fluid delivered from this section then passes through the low pressure section or sections of the turbine. As illustrated the low pressure sections are equipped with reaction blades and are capable of expanding the fluid down to exhaust or condenser pressure. It will, of course, be understood that if desired, one or more impulse stages may be employed and that the low pressure section may be materially modified without departing from the invention.

In the turbine shown, the motive fluid delivered from the blades 13 is received by an annular chamber 15, which communicates with the inlet end of the low pressure section and also with a passage 16, which extends around a section 17 of the low pressure section and communicates with an annular chamber 18, formed within the casing 5.

The section 17 may for convenience of description and also for the purpose of conforming to accepted nomenclature, be termed the intermediate section of the turbine 10, and this section, under certain conditions of operation, is by-passed by motive fluid passing through the by-pass passage 16. The fluid is delivered by the passage 16 to the chamber 18 and from the chamber 18 to the first row of stationary blades of the working

section located immediately adjacent to the intermediate section 17, which, for the reasons above assigned, may be termed the low pressure section 19 of the turbine 10. This section 19 is a full peripheral admission section and communicates with the exhaust passages formed within the casing 5 and through them with the exhaust port and the condenser, which is not shown. Communication between the chamber 15 and the bypass 16 is controlled by means of a valve 21 which, in the drawings, is shown as being capable of manual control, since it is provided with an operating hand wheel 22. The casing 5 of the turbine 10 also incloses a reversing stage or turbine which, as illustrated, consists of a series of expansion nozzles 23 and coöperating impulse blades 24. The blades 24 are shown mounted on a wheel 25, which forms a part of the rotor 4. The nozzles 23 communicate with a port 26, which is formed in the casing and is adapted to communicate with a source of high pressure fluid supply through pipe 27. It will, of course, be understood that two or more stages may be employed in the reversing turbine and that this turbine may be of any desired type or combination of different types; for example, it may be a combination of the impulse and reaction types of turbine sections such as the turbine 10 just described. As illustrated, the motive fluid, discharged from the last row of blades 24, enters the exhaust passages formed within the casing 5 and is discharged into the condenser.

In the drawings I have diagrammatically shown means for hermetically separating the ahead turbine 10 from the reversing turbine, which consists of an ordinary labyrinth packing or fluid seal. This packing is formed by means of alternately arranged and interleaving rotating and stationary annular ridges which are respectively mounted on a drum 27 of the rotor 4, and on an internal ring 28, which is mounted on the casing 5 and is located between the rotor wheels 14 and 25. The drum 27 may be so proportioned that it may be employed in counter-balancing the end thrust imparted to the rotor by the fluid traversing the low pressure sections of the turbine 10.

The turbine 10^a, in effect, supplements the low pressure section 19 of the turbine 10. It receives motive fluid from the chamber 15 which is delivered through piping 31 to inlet ports provided within the casing 7. Communication between the chamber 15 and the turbine 10^a is controlled by means of a valve 32 which, as shown, is located in the piping 31 and is preferably adapted to be manually controlled.

As illustrated, the turbine 10^a is a straight double flow turbine, that is to say, motive fluid delivered to it is divided into two sub-

stantially equal streams and passes through two bilateral symmetrical working passages toward both ends of the turbine. The turbine 10^a is provided with two reaction sections 33 and 33', which are located at opposite ends of the casing 7 and through which motive fluid is adapted to pass in opposite axial directions toward exhaust passages 34, located in each end of the casing 7. I how-
 10 ever do not desire to limit the invention to the use of reaction turbine elements in the sections 33 and 33' of the turbine 10^a, since turbine sections of any desired type may be substituted for these sections. The turbine 15 is also shown as provided with a single row of impulse blades 35, which are mounted on a wheel 36, forming a part of the rotor 6 and located midway between the sections 33 and 33'. These blades 35, together with op-
 20 positely disposed nozzles 37 and 37' (diagrammatically shown in Fig. 1), comprise what may be termed the primary stage of the turbine 10^a, but which is adapted to operate as a part of the low pressure section 25 of the turbine 10, when the turbines 10 and 10^a are coöperating, or functioning as an organized apparatus or single turbine formed in two sections. The nozzle or series 30 of nozzles 37 are located on one side of the wheel 36, and deliver motive fluid to the re-
 action section 33 of the turbine, after having partially expanded the fluid and dis-
 charged it into the blades 35. On the other 35 hand, the nozzle or series of nozzles 37' are located on the opposite sides of the wheel 36, and after partially expanding the motive fluid, deliver it to the blades 35 in such a way that it is delivered to the blades of the section 33', after it has passed through the 40 blades 35.

In the drawings diagrammatic means are shown for dividing the motive fluid, delivered from the chamber 15 of the turbine 10, into two streams and for delivering it to the nozzles 37 and 37' of the turbine 10^a, but it will be apparent, to those skilled in the art, that various means may be employed for accomplishing both the division of the fluid into two streams and the delivery of the 45 separate streams to the separate sections of the turbine, and that each of the nozzles or separate groups of nozzles 37 and 37' may be separately controlled by means of valves or other devices ordinarily employed to obtain what is termed, nozzle control. It will also be understood that the nozzles 37 and 37' have equal areas and are identical in 50 design so that the pressure drop through them is substantially equal. It will be understood, however, that the existing space, around portions of the wheel 36, which communicates with the space on both sides of the wheel will operate as an equalizing passage should there be any tendency to create 55 differences of pressure on opposite sides of

the wheel due to slight variations in the nozzles 37 and 37'. It will also be understood that the velocity energy of the motive fluid, rendered available by its partial expansion in passing through the nozzles, may be fractionally abstracted and that two or more rows of impulse blades may be employed instead of the single row shown. 70

Both the turbines 10 and 10^a are shown directly connected to a separate pinion shaft 75 of a reduction gearing 38, which may be employed in driving any apparatus to be driven, such, for example, as the propeller shaft of a vessel. The reduction gearing illustrated is provided with a gear 39, mounted on a shaft 41, and two pinions 42 and 42^a, both of which mesh with the gear 39, but are located on diametrically opposite sides of it. The pinion 42 is mounted on a shaft 43 which is directly connected to the 80 turbine 10 by means of a flexible coupling 44 or, if desired, a clutch mechanism capable of being disengaged. The pinion 42^a is mounted on a shaft 43^a which is directly connected to the turbine 10^a by means of a 85 flexible coupling 44^a, or a clutch mechanism capable of being disengaged. The pinions 42 and 42^a shown, are of the same size and consequently the turbines 10 and 10^a illustrated are so constructed that they operate 90 at the same speeds while operating as component parts of an organized apparatus or as separate sections of a single turbine. While it is preferable to operate the two turbines at the same speed, it will be apparent that the two turbines may operate at 95 different speeds. 100

While the two turbines are operating as an organized apparatus, motive fluid is delivered through port 11 to the nozzles 12 of 105 the turbine 10. The nozzles 12 partially expand the motive fluid and deliver it to blades 13. After traversing the blades 13, approximately one-third of the motive fluid is delivered through the by-pass 16 to the 110 low pressure section 19 of the turbine 10, while the remaining two-thirds is delivered through the piping 31 to the nozzles 37 and 37' of the turbine 10^a. These nozzles, as has been described, partially expand the fluid 115 traversing them and deliver it to a row of impulse blades 35 in such a way that approximately one-half of the motive fluid, received from the turbine 10, traverses the section 33 of the turbine 10^a, while the other 120 half traverses the section 33'. With such an arrangement three separate working passages are provided through which the motive fluid passes to the condenser, and consequently each of the turbines may be materially reduced in diameter below that of a single flow turbine of the same power and of the same area through the last few rows 125 of low pressure blades. In fact, the diameters of the separate turbines, forming com- 130

ponent parts of the illustrated embodiment of my invention, need only be 57% of the diameter of the single flow turbine to which I have referred; and in addition to this, the 5 blades of the triple flow stage are approximately but 57% of the length of the blades of a single flow turbine of equal power and blade area. Such blades are about 5.3 times as rigid as the blades required in the single flow turbine.

While the reduction in the diameter of the two turbines 10 and 10^a increases the leakage of fluid through the clearance space between the ends of the turbine blades and the 15 casings, this slight loss is more than offset by the fact that there is but one counter-balancing piston or dummy and that the diameter of this dummy is but 57% of the diameter of the counterbalancing piston, 20 which would be employed in the single flow turbine of the same power; the loss is further offset by the fact that the blade and dummy clearances may safely be much smaller than in the single flow turbine because of the smaller diameters of the rotors 25 and the shorter blades employed. The actual difference in the total leakage of fluid through the clearance spaces of the turbine is almost negligible and the small loss in 30 efficiency resulting from the small difference, which may exist, is more than offset by the mechanical efficiency of the apparatus.

It is well known that rotation losses in a 35 turbine vary directly as the cube of the revolutions per minute of the rotor and as the fifth power of the diameter of the rotor; hence a reduction by one-half of the diameter of the rotor and a doubling of the revolutions per minute of the rotor (giving 40 the same blade speed in each case) results in reducing the rotation losses to 25% of the rotation losses in a single flow turbine of the same power.

The principal advantage gained by employing apparatus embodying my invention 45 is, however, the betterment of the economy at cruising speeds and also the great reduction in the weight of the turbine.

While the turbine is running at low speed, 50 and consequently at reduced power, the valves 21 and 32 are closed; this shuts off the supply of motive fluid to the turbine 10^a and therefore all of the fluid delivered to the nozzles 12 of the turbine 10 must pass 55 through the intermediate and low pressure sections of that turbine. Inasmuch as the motive fluid has but one path to the condenser and that path is approximately but one-third of the area available while the turbine 60 10^a is receiving fluid from the turbine 10, the absolute fluid pressure at the inlet end of the intermediate section or in the chamber 15 will be three times as high as it would be if the valve 32 were open, or as it 65 would be in a single flow turbine developing

the same power under the same conditions. The turbine 10 may be so designed that the closing of both of the valves 21 and 32 will increase the absolute pressure in the chamber 15 to about 5 or 6 times what it would 70 be with the valves open, or what the pressure would be in a single flow turbine of equal power operating under similar conditions. It will also be apparent, to those skilled in the art, that the successive closing off of 75 nozzles of both the sets 37 and 37' will accomplish, in a measure, what is accomplished by closing the valve 32 and that the economy of the organized apparatus is improved at all powers between that developed with the 80 valve 32 wide open and the power developed with the valve closed; in other words, the use of nozzle control in the turbine 10^a produces substantially the same effect as the gradual closing of the valve 32 as the load 85 decreases; but it eliminates the losses in economy which would result due to throttling of the fluid. The result gained by closing the valve 32 is that the expansion range 90 of the impulse portion of the turbine is reduced, and the expansion ratio of the reaction portion or low pressure sections is increased, thus increasing the efficiency of the turbine and insuring high economy during 95 cruising speeds. This result is, of course, more marked with both the valves 21 and 32 closed. It may be said that the turbine apparatus embodying my invention, in effect, 100 includes a specially designed cruising turbine which is capable of running at one-third speed and of developing one-thirtieth of the power of the organized turbine apparatus with high economy. The economy of this cruising turbine is substantially the same at cruising speeds as the economy of 105 the entire or organized apparatus, while it is developing full power and running at full speed, because the reaction blades or separate stages of the turbine 10 are designed to meet conditions of reduced speeds; that is, it 110 has a large number of rows of blades or stages, while the turbine 10^a has but a few rows of blades or stages since it, the turbine 10^a, operates only while the organized turbine apparatus is developing full power, at 115 which time the blade speed is high, and therefore only a few rows of blades are required. It will be understood by those skilled in the art that the intermediate section 17 of the turbine 10 is diagrammatically shown and that it is of reduced length for convenience of illustration only, and may in practice include a relatively large number of rows of blades or stages as compared with the number of rows of blades or 120 stages included in each separate low pressure section. By stage I mean a working section of a turbine in which the steam or motive fluid is expanded or reduced in pressure and approximately all of the velocity 125 130

130

or kinetic energy occasioned by the expansion is abstracted. Each stage of the low pressure section of the turbine 10 includes but one row of moving blades whether the section is of the reaction or some other type not embodying the reaction principle.

A great reduction in weight is obtained by my invention over the weight of ordinary marine turbines operating under similar 10 conditions and developing the same power, because the smaller diameters of the rotor elements permit relatively high speeds and also because only a relatively small portion of the total blading need be designed for 15 low speed conditions. This reduction in weight is advantageous both in the operation of erecting the apparatus and in its use as the propelling apparatus of a vessel, since, 20 in the first place, the parts of the small units can be easily and quickly handled, and in the second place, the reduction in weight reduces the fixed tonnage of the vessel and consequently renders it capable of carrying 25 a greater tonnage of fuel or cargo than would be the case if it were equipped with an ordinary marine turbine.

A further advantage is that the organized 30 turbine apparatus embodying my invention occupies less space than ordinary turbines and there is no independent cruising turbine or engine with the accompanying gears. In addition to this, the steam piping is also 35 materially simplified and the turbine is well adapted to be employed with a condenser which may be located beneath it.

Another principal advantage obtained by 40 my invention is that either the turbine 10, the turbine 10^a or the reversing turbine may develop full power while operating independently. In case the turbine 10^a is incapacitated, high pressure motive fluid is delivered to the turbine 10 and the by-pass valve 21 is open, but the valve 32 is closed. This increases the pressure in the chamber 45 to such an extent that practically the same weight of motive fluid will pass through the low pressure section of the turbine 10 as ordinarily passes through the sections 19, 33, and 33' while the valve 32 is open. If the turbine 10 is incapacitated, high pressure motive fluid may be admitted 50 directly to the turbine 10^a and it, under such conditions, will develop full power with a small loss in efficiency. In Fig. 2 of the 55 drawings I have shown a sectional view of the turbine 10^a provided with nozzles 45 and 45' for delivering high pressure motive fluid to the blades 35 of the turbine. The casing 7 is provided with two ports 46 and 60 46', which are adapted to communicate with a source of high pressure fluid through pipes not shown and which communicate respectively with the nozzles 45 and 45'. It will be seen from the foregoing that practically 65 full speed can be maintained during

emergencies with any two of the turbines out of commission. This is particularly advantageous in naval vessels since a small loss in economy is of little importance during emergencies in which it is essential to obtain 70 high speeds.

In Fig. 3 of the drawings I have diagrammatically illustrated a turbine or organized 75 turbine apparatus embodying my invention, which is well adapted to be employed as the driving agent of a ship's propeller and which may be utilized in connection with a reduction gearing if desired. While the turbine illustrated in Fig. 3 embodies some 80 of the features of the turbine illustrated in Fig. 1, it is well adapted to be employed as the propelling agent, for example, of a merchant vessel in which the difference between the two desirable speeds is not as great as the difference between cruising speed and 85 full speed of a naval vessel.

The organized turbine apparatus as illustrated 90 consists of two separate turbines or turbine elements 10^b and 10^c so arranged that the turbine 10^c forms in effect a portion 95 of the low pressure section of the turbine 10^b, while the two turbines are operating together, or, in other words, while the organized turbine apparatus is developing full power.

The turbine 10^b, as illustrated, includes an initial stage of the impulse type, which consists of expansion nozzles 48 and two rows of blades 49. The motive fluid, after having been partially expanded by the nozzles 100 48, is delivered to the blades 49 and then is discharged into an annular chamber or passage 51 which communicates with, what may be termed, an intermediate section 52 of the turbine 10^b or of the entire organized apparatus. This section, as conventionally illustrated, is of the reaction type and is arranged to deliver motive fluid, traversing it, to an annular chamber 53, which is formed within the casing of the turbine 10^b and 105 which communicates with what may be termed one section 54 of the low pressure stage of the organized turbine apparatus. This section 54 is inclosed within the casing of the turbine 10^b and is, in fact, the low 110 pressure section of that turbine. It is conventionally shown as of the reaction type and as discharging into an exhaust passage 55 formed in the casing and adapted to communicate with a condenser, which is not 115 shown, but it may be of any suitable type.

The chamber 53 is provided with a delivery port 56 and the motive fluid delivered to it is divided into two streams, one of which passes through the section 54, while 120 the other is delivered through the piping 56^c to the inlet port of the turbine 10^c. As illustrated, the turbine 10^c is a straight 125 double flow turbine, that is, one in which the motive fluid is delivered at a central 130

point, with reference to the casing, and is divided so that it flows in opposite axial directions toward the ends of the casing in passing through the working passages of the turbine. As conventionally shown, the turbine 10^c is provided with two oppositely located sections 57 and 57' which are similar to each other and which are so constructed that the area through the last few rows of blades at the discharge end of each section is equal to the area through the last few rows of blades of the section 54 of the turbine 10^b . However, the section 54 is preferably provided with a greater number of rows of blades than either of the sections 57 and 57'. With the arrangement described, twice as much motive fluid is delivered through the piping 56^c as passes through the section 54 of the turbine 10^b when the valve 58 in the piping is open.

The casing of the turbine 10^c , like that of the turbine 10, incloses a reversing turbine 59, which receives motive fluid through a port 61 formed in the casing and which is separated from the initial stage of the turbine 10^b by means of a fluid seal 62, the cylinder of which may be employed as a counterbalancing piston in counterbalancing the end thrust imparted to the rotor of the turbine by the reaction stage.

While the organized turbine apparatus illustrated is developing full power, motive fluid is delivered through the nozzles 48 of the turbine 10^b , and the valve 58 is open so as to establish communication between the chamber 53 and the inlet port of the turbine 10^c . Under such conditions, the motive fluid, after having been partially expanded in traversing nozzles 48, is delivered to the blades 49 where the available velocity energy is abstracted. The motive fluid, on leaving the blades 49, enters the intermediate section 52 in which it is fractionally expanded by the successive rows of reaction blades. It will be apparent that instead of employing straight reaction blades, the available energy may be abstracted from the motive fluid by impact and reaction in which the motive fluid is fractionally expanded in both the rotary and the stationary blades, or that any other type of blading may be employed. After the motive fluid has traversed the section 52 of the turbine, it is delivered to the chamber 53 and is divided into two separate streams, one of which passes through the section 54, while the other of which is delivered to the turbine 10^c and is again divided into two substantially equal streams which pass through the separate sections 57 and 57' of the turbine 10^c .

When it is desired to propel at low speeds a vessel, equipped with the turbines illustrated, the valve 58 is closed and consequently the range of expansion through the low-pressure sections of the turbine 10^b

increased, while the pressure drop through the nozzles 48 is diminished. This causes the turbine 10^b to operate efficiently at the low speed, while the rotor of the turbine 10^c is caused to rotate in a vacuum or in an atmosphere of attenuated vapor unless means are employed for uncoupling it from the pinion of the reduction gearing with which it may be employed. It will also be apparent that either of the turbines 10^b or 10^c may be employed in driving the vessel at substantially full speed, even though one of them is incapacitated. In case the turbine 10^c is incapacitated, high pressure motive fluid is delivered directly to the inlet port 80 of the turbine 10^c , through piping 60, the valve 58, of course, being closed. If the turbine 10^c is incapacitated, the turbine 10^b is caused to operate at full speed by increasing the amount of steam, delivered to it, over 85 that normally delivered while it is operating in conjunction with the turbine 10^c .

In both the illustrated embodiments of my invention a portion of the organized apparatus is revolving idly during operation 90 at low speeds, at which time the heating effect, due to the windage and friction of the blades, is so small that the temperature rise is of no consequence and will not cause distortion of the turbine cylinder and the 95 consequent contact of the moving and stationary elements; whereas in all other marine turbine installations in which provision is made for obtaining good economy at low cruising speed, the turbine elements 100 employed during cruising or low power conditions are revolving idly during high speed or full power conditions. It is well known that the friction and windage loss occasioned by rotating a turbine element in an atmosphere of steam is directly proportional to the cube of the revolutions per minute and is also directly proportional to the density of the steam surrounding the rotating element, consequently, since the low pressure 105 element in my turbine is revolving idly in steam at condenser pressure and only when the speed is reduced, for example, to about three-fourths of full speed, the heating 110 encountered under the most disadvantageous 115 conditions will be but 42% of the heating encountered in turbines in which separate 120 cruising elements are revolved idly at full speed; hence, since the greater portion of all the trouble encountered in marine installations, and particularly installations on naval vessels, has been due to contact of the moving and stationary parts of the cruising turbine, while the main turbine is developing full power, the elimination of this difficulty 125 constitutes one of the principal features of my invention.

In both embodiments of my invention I have shown the low pressure turbine as a double flow turbine, but it will be apparent 130

that this isolated section of the high pressure turbine may be single flow if desired, or in fact, it may itself be divided into three or more sections, some of which are located in separate casings.

While I have illustrated but two embodiments of my invention, I desire it to be understood that various changes, modifications, substitutions, omissions, and additions 10 may be made in the apparatus illustrated without departing from the spirit and scope of my invention as set forth by the appended claims and that I do not limit my invention to marine installations, nor use in connection with reduction or transmission gearing.

Having thus described my invention, what I claim is:

1. A power generating system comprising 20 a turbine having a high pressure turbine element, a divided low pressure turbine element communicating therewith, the separate sections of which are arranged to operate in parallel, one of the sections of the 25 divided low pressure turbine element being isolated by being located in a separate casing and being adapted to receive fluid from the high pressure element while the turbine is operating at full power and at high speed, 30 and means for shutting off the fluid to the isolated section when the turbine is operating at low speed and at reduced power.

2. A turbine comprising an impulse stage and a full peripheral admission low pressure 35 section, in combination with an isolated low pressure section located in a separate casing and adapted to operate in parallel with said first mentioned low pressure section, and means for delivering a portion of the 40 motive fluid discharged from the impulse stage of the turbine to the isolated section when the combined apparatus is developing full power.

3. In an apparatus of the character described, a turbine having a working passage 45 for expanding motive fluid from initial to exhaust pressure, and a low pressure turbine for receiving motive fluid from said first mentioned turbine and for expanding 50 the motive fluid so received to exhaust pressure, in combination with a transmission gearing comprising a driven gear, a driving gear intermeshing with said driven gear and coupled to said first mentioned turbine, and 55 a second driving gear intermeshing with said gear and coupled to said low pressure turbine.

4. In an apparatus of the character described, a turbine in which motive fluid is 60 expanded from initial to exhaust pressure, a second turbine having oppositely extending working passages, each adapted to expand motive fluid from an intermediate to exhaust pressure, and means for delivering 65 motive fluid from an intermediate portion

of the working passage of the first turbine to the inlet of the second turbine.

5. In an apparatus of the character described, a turbine comprising a high pressure section and a low pressure section in 70 which motive fluid is expanded from initial to exhaust pressure, a second turbine having a divided working section adapted to operate in parallel with the low pressure section of the first turbine, and means for delivering motive fluid from an intermediate point of the working passage of the first to the inlet of the second turbine.

6. A turbine comprising a single flow high pressure stage and a low pressure turbine 75 element divided into three separate sections, two of said sections being inclosed within a separate casing.

7. A turbine comprising a single flow high pressure section and a low pressure 80 working portion divided into three separate low pressure sections operating in parallel, and each receiving motive fluid from said high pressure section, at least one of said 85 low pressure sections being located in the same casing with said high pressure section, and at least one of said low pressure sections being isolated by being located in a 90 separate casing.

8. A turbine comprising a high pressure 95 turbine element, a low pressure turbine element divided into three separate sections, two of said sections being inclosed within a 100 separate shell through which the motive fluid flows in opposite directions, and means for controlling the delivery of motive fluid to said shell.

9. A turbine comprising a single flow section and a double flow section, and means 105 for delivering motive fluid to the double flow section from a point of intermediate pressure of the single flow section.

10. An apparatus of the character described comprising a turbine, a low pressure 110 turbine communicating with an intermediate portion of the working passage of the first mentioned turbine, and means for bypassing fluid around a section of the working passage of the first mentioned turbine, to the low pressure turbine, contained within the same casing as the high pressure turbine.

11. An apparatus of the character described comprising a turbine, a low pressure 115 turbine communicating with the working passage of the first mentioned turbine at a point of intermediate pressure, means for bypassing motive fluid around a portion of the working passage of the first mentioned turbine, and means for controlling the delivery of motive fluid through 120 said by-pass to low pressure stage of the first mentioned turbine.

12. An apparatus of the character described comprising a turbine, a low pres-

- sure turbine communicating with the working passage of the first-mentioned turbine at a point of intermediate pressure, a bypass for by-passing motive fluid around a 5 section of the working passage of the first mentioned turbine, a valve for controlling the delivery of motive fluid through the bypass, and a valve for controlling communication between the low pressure turbine and 10 said first mentioned turbine.
13. A turbine having a high pressure stage and a low pressure section communicating with the high pressure stage and divided into separate divisions each adapted 15 to operate in parallel, one of said divisions being designed for different speed conditions from the other.
14. A turbine having a high pressure turbine element, a low pressure turbine element 20 communicating therewith and comprising separately formed sections adapted to operate in parallel, one of said sections being constructed for different speed and pressure conditions than the other, and means 25 for shutting off communication between a section of the low pressure turbine element and the high pressure turbine element.
15. A turbine having a high pressure stage, a low pressure turbine element communicating therewith and comprising independently formed separate sections adapted 30 to operate in parallel, one of said sections being constructed to operate efficiently at different speed and pressure conditions from 35 the other, and means for shutting off communication between a section of the low pressure turbine element and the high pressure stage.
16. A turbine having a high pressure turbine element and a divided flow low pressure 40 turbine element formed in separate sections adapted to operate in parallel, one of said sections being formed independently of the other and being constructed to operate 45 with high efficiency at different speed conditions from the other, a by-pass communicating with the low pressure turbine element, and 50 means for controlling the flow of fluid through the by-pass.
17. A turbine having a high pressure portion and a low pressure portion through which motive fluid successively flows, said 55 low pressure portion being formed in separate sections with each of said sections communicating with the high pressure portion and with one of said sections independently formed and designed to give highest efficiency 60 at different speed and pressure conditions from the other, and means for shutting off communication between said independently formed section and the high pressure portion of the turbine.
18. A turbine comprising an initial stage, 65 a divided flow low pressure section and a reversing section, said initial stage, one division of the low pressure section and said reversing section having a common casing and a common rotor, and the other division 70 of the low pressure section having an independent casing and rotor.
19. A turbine comprising an initial section, a divided flow low pressure section, and a reversing section, said initial section, one 75 division of said low pressure section, and said reversing section having a common rotor element, and a counterbalancing piston located between the initial section and the reversing section of the turbine.
20. An apparatus of the character described comprising a turbine, a second turbine, means for delivering motive fluid from the first mentioned to the second turbine, a bypass 80 communicating with said means for bypassing a section of the working passage of the first mentioned turbine, means for shutting off communication between the turbines, means for closing the bypass, and means for delivering high pressure motive 85 fluid to the second turbine.
21. An apparatus of the character described, comprising a turbine, means for bypassing fluid entering the inlet of the turbine around a section of the working passage 90 thereof, a low pressure turbine, and means communicating with the first mentioned turbine, at a point ahead of the inlet to the bypass, for delivering motive fluid to the low pressure turbine.
22. A turbine comprising a high pressure stage, a full peripheral admission low pressure section having a single row of moving blades per stage, in combination with an isolated low pressure section adapted to operate 95 in parallel with the first mentioned low pressure section, and means for simultaneously delivering fluid discharged from said high pressure stage to both of said low pressure sections while the combined apparatus 100 is developing full power.
23. An apparatus of the character described comprising a turbine, having a divided low pressure section, one division of which is isolated by being located in a separate casing, and means for cutting off the supply of motive fluid to the portion of the low pressure section having the separate casing while operating the turbine at low 105 speed.
24. An apparatus of the character described, comprising a turbine having a divided flow low pressure section, one division of which is located in a separate casing, a gearing driven by the turbine and independently by the isolated portion of the low pressure section, and means for shutting off the motive fluid supply to the isolated portion of the low pressure stage when the turbine is operating at low speed.

25. An apparatus of the character described, comprising a turbine having a divided low pressure section, one division of which is isolated by being located in a separate casing, means for by-passing motive fluid around an intermediate portion of the turbine while the turbine is operating under full load, and means for shutting off the supply of motive fluid to the isolated section of the turbine while the turbine is operating under light load.

26. A turbine comprising a high pressure section having a plurality of fluid admission nozzles, means for varying the number of nozzles effective in delivering motive fluid to the blades or buckets of said sections, and a full peripheral admission low pressure section receiving motive fluid from the high pressure section, and in which a single row 20 of moving blades is employed in each stage, in combination with a section isolated by being located in a separate casing from said high and low pressure sections, and means for simultaneously delivering motive fluid 25 discharged from the high pressure section to the low pressure section and the isolated section while the combined apparatus is developing full power.

27. A power generating system comprising 30 a variable or partial peripheral admission impulse high pressure section, two low pressure sections at times adapted to operate in parallel on the fluid exhausted from said high pressure section, at least one of said sections being isolated by being located in a separate casing from the high pressure section, and means, such as a valve, for cutting off the supply of motive fluid to the isolated section when the system is operating at reduced speed and is developing reduced power, and for delivering fluid from said high pressure section to said isolated section when the system is developing full power.

28. A power generating system comprising 45 a multiple velocity drop impulse turbine element, two or more independent low pressure turbine elements adapted to operate in parallel and to receive motive fluid from said impulse turbine element, at least one of said low pressure elements being isolated from the impulse turbine element by being located in a separate casing, and means for shutting off the supply of motive fluid to said isolated low pressure elements when the system is developing reduced power.

29. A marine turbine system consisting 60 of a high pressure turbine section and two low pressure sections designed to operate at the same terminal pressure, one of said low pressure sections being located in the casing with the high pressure section, the other low pressure section being in a separate casing and on a separate shaft, both low pressure sections being adapted to operate in parallel on the exhaust from the high pres-

sure section when the system is developing full power.

30. A marine turbine system comprising a turbine element, having a high pressure section and a low pressure section located 70 in the same casing, a second turbine element located in a separate casing adapted to operate in parallel with the low pressure section and to receive motive fluid from the high pressure section, a transmission gearing operatively connected to the shafts of both of said turbine elements and means for cutting off the supply of motive fluid to said second turbine element when the system is developing reduced power.

31. A marine turbine system comprising a turbine element having a high pressure section and a low pressure section located in the same casing and having a common rotor element, in combination with a second turbine element located in a separate casing, having a separate rotor element, and adapted to operate in parallel with the low pressure section and to receive motive fluid from the high pressure section of said first 90 mentioned turbine element, a transmission gearing comprising a gear operatively connected to apparatus to be driven and two gears meshing therewith, each operatively connected to the rotor element of one of 95 said turbine elements, and means for shutting off the supply of motive fluid to said second turbine element when the system is developing reduced power.

32. A marine turbine system, comprising 100 a high pressure turbine element, a separate low pressure turbine element receiving motive fluid from said high pressure element and operating in parallel with a low pressure section thereof, a transmission gearing including two driving gears to each of which the rotor of one of said turbine elements is connected, means for shutting off the delivery of motive fluid from the high pressure turbine element to the low pressure 110 element when the system is developing reduced power and means for delivering high pressure motive fluid to said element.

33. A marine turbine comprising a high pressure turbine element having a high 115 pressure section and a low pressure section adapted to receive motive fluid from the high pressure section and located in the same casing as the high pressure section, a low pressure turbine element located in a 120 separate casing and having fluid inlet nozzles for delivering motive fluid to the working elements thereof, and means for delivering motive fluid from the high pressure turbine element to the nozzles of the low pressure turbine element and to the low pressure section while the marine turbine is developing full power.

34. A marine turbine comprising a high 125 pressure turbine element having a high

- pressure section and a low pressure section located in the same casing and having a common rotor element, a low pressure turbine element having a separate casing and 5 rotor element adapted to operate in parallel with said low pressure section but designed for different power and speed conditions from said low pressure section, and a transmission gearing having two driving gears, 10 each operatively connected to the shaft of one of said turbine elements, and means for delivering motive fluid from the high pressure turbine element to the low pressure section and to the low pressure turbine 15 element when the marine turbine is developing full power.

35. A marine turbine comprising a high pressure turbine element, having a high pressure section and a low pressure section 20 adapted to receive motive fluid from the high pressure section, a low pressure turbine element having a separate rotor element and separate casing and adapted to receive motive fluid from said high pressure section 25 and to operate in parallel with said low pressure section when the marine turbine is developing full power, a transmission gearing having a plurality of driving gears, one being operatively connected to the rotor 30 of the low pressure section and one to the rotor of the low pressure turbine element.

36. A marine turbine comprising a high pressure turbine element having a high pressure section and a low pressure section 35 adapted to operate in series, a low pressure turbine element designed for different power and speed conditions from said low pressure section and having a separate rotor and stator but adapted to receive motive 40 fluid from said high pressure section and to operate in parallel with said low pressure section when the marine turbine is developing full power, a transmission gearing including a plurality of driving gears, one being operatively connected to the rotor element of the low pressure section and one to the rotor element of the high pressure turbine element, and means for cutting off the 45 supply of motive fluid from the high pressure section to the low pressure turbine element when the marine turbine is operating at low speed, and for delivering high pressure motive fluid to the low pressure turbine element to operate it independently of 50 the high pressure turbine element.

37. A marine turbine comprising a high pressure turbine element, having a high pressure impulse section to which motive fluid is delivered through nozzles, two full 60 peripheral admission low pressure sections at times adapted to operate in parallel on the fluid discharged from the high pressure section and at least one of which is isolated by being located in a separate casing from 65 the impulse section, a transmission gearing

having a separate driving gear operatively connected to the rotor element of each low pressure section, means for shutting off the delivery of motive fluid to the isolated section when the marine turbine is developing 70 reduced power, and a reversing turbine operatively connected to said transmission gearing.

38. A turbine comprising a variable or partial admission high pressure section, a plurality of full peripheral admission low pressure sections adapted to operate in parallel on the fluid discharged from the high pressure section, at least one of which is isolated by being located in a separate casing from the high pressure section and is designed for different speed conditions from the other, and means for shutting off the supply of motive fluid from the high pressure section to the isolated section when the turbine is developing reduced power.

39. A turbine comprising a variable or partial admission high pressure section, a plurality of full peripheral admission low pressure sections adapted to operate in parallel on the fluid discharged from the high pressure section, at least one of which is isolated by being located in a separate casing, and means for shutting off the supply of motive fluid to said isolated section when 95 said turbine is developing full power.

40. A turbine comprising a variable or partial admission high pressure section, a plurality of full peripheral admission low pressure sections adapted to operate in parallel on the fluid discharged from the high pressure section, at least one of which is isolated by being located in a separate casing from the high pressure section and is designed for different speed conditions from 100 the other, means for shutting off the supply of motive fluid from the high pressure section to the isolated section when the turbine is developing reduced power, and a transmission gearing having a separate driving gear operatively connected to the rotor element of the high pressure section and a separate driving gear operatively connected to the 105 rotor element of the isolated section.

41. A turbine comprising a variable or partial admission high pressure section, a plurality of full peripheral admission low pressure sections adapted to operate in parallel on the fluid discharged from the high pressure section, at least one of which is isolated by being located in a separate casing, means for shutting off the supply of motive fluid to said isolated section when said turbine is developing reduced power, and a transmission gearing having a separate driving gear operatively connected to the rotor element of the isolated section.

42. A turbine having a high pressure section and a plurality of low pressure sections adapted to operate in parallel on the fluid 130

discharged from the high pressure section, one of said sections being isolated by being located in a separate casing from the high pressure section and being designed for different speed conditions from the other, means for shutting off the supply of motive fluid from the high pressure section to the isolated section when the turbine is developing reduced power, and a transmission gearing having a driving gear operatively connected to the rotor of said high pressure section.

43. A turbine system comprising a high pressure turbine element having a variable or partial peripheral admission high pressure section, and a full peripheral admission low pressure section receiving motive fluid from the high pressure section and located in the same casing therewith, a low pressure turbine element adapted to operate in parallel with said low pressure section on motive fluid delivered from said high pressure section and having a partial peripheral admission initial section receiving motive fluid from said high pressure section, and a full peripheral admission section receiving motive fluid from said initial section, and means for shutting off the supply of motive fluid from said high pressure section to said low pressure turbine element when the turbine system is developing reduced power.

44. A turbine system comprising a high pressure turbine element having a variable or partial peripheral admission high pressure section, and a full peripheral admission low pressure section receiving motive fluid from the high pressure section and located in the same casing therewith, a low pressure turbine element adapted to operate in parallel with said low pressure section on motive fluid delivered from said high pressure section and having a partial peripheral admission initial section receiving motive fluid from said high pressure section, and a full peripheral admission section receiving motive fluid from said initial section, means for shutting off the supply of motive fluid from said high pressure section to said low pressure turbine element when the turbine system is developing reduced power, and a reversing section operatively connected to said turbine system.

45. A turbine system comprising a high pressure turbine element having a variable or partial peripheral admission high pressure section, and a full peripheral admission low pressure section receiving motive fluid from the high pressure section and located in the same casing therewith, a low pressure turbine element adapted to operate in parallel with said low pressure section on motive fluid delivered from said high pressure section and having a partial peripheral admission initial section receiving motive fluid from said high pressure section, and a full

peripheral admission section receiving motive fluid from said initial section, means for shutting off the supply of motive fluid from said high pressure section to said low pressure turbine element when the turbine system is developing reduced power and means for delivering high pressure motive fluid to said low pressure turbine element.

46. A turbine system comprising a high pressure turbine element having a variable or partial peripheral admission high pressure section, a full peripheral admission intermediate section, and a full peripheral admission low pressure section, all operating in series and located in the same casing, a by-pass around the intermediate section, a low pressure turbine element located in a separate casing, adapted to operate in parallel with the low pressure section and designed for different speed conditions from the low pressure section, means for controlling the delivery of fluid through the by-pass, and means for delivering motive fluid from the inlet end of the by-pass to said low pressure turbine element when the system is developing full power.

47. A turbine system comprising a partial peripheral admission high pressure section, an intermediate pressure section, a full peripheral admission low pressure section, all of said sections operating in series, a low pressure turbine element adapted to receive motive fluid from said high pressure section and to operate in parallel with said low pressure section, means for by-passing said intermediate pressure section, and means for delivering fluid to said low pressure turbine element when said system is developing full power.

48. A turbine system comprising a partial peripheral admission high pressure section, an intermediate pressure section, a full peripheral admission low pressure section, all of said sections operating in series, a low pressure turbine element adapted to receive motive fluid from said high pressure section and to operate in parallel with said low pressure section, means for by-passing said intermediate pressure section, means for delivering fluid to said low pressure turbine element when said system is developing full power, and a transmission gearing between said system and the apparatus to be driven thereby having a driving gear operatively connected to the rotor of said high pressure section and a separate driving gear operatively connected to the rotor of said low pressure turbine element.

49. A power developing system, comprising an initial section to which high pressure motive fluid is delivered, a plurality of low pressure sections operating in parallel on the fluid discharged from said high pressure section, at least one of said low pressure sections being isolated by being located

in a separate casing from the initial section, a power transmission shaft driven by the rotor element of the initial section, a separate power transmission shaft driven by the 5 rotor element of the isolated section, and means for cutting off the fluid supply to the isolated section when the transmission system is developing reduced power.

50. A power developing system comprising a high pressure section, two low pressure 10 sections operating in parallel on fluid discharged from the high pressure section, one of said low pressure sections being designed to operate efficiently at a different speed 15 from the other and isolated by being located

in a separate casing from the high pressure section, means for cutting off the supply of fluid to the low pressure section when the system is developing reduced power, and separate power transmission shafts oper- 20 atively connected to the rotor element of the high pressure section and to the rotor ele- ment of the isolated section.

In testimony whereof, I have hereunto subscribed my name this 10th day of Sep- 25 tember, 1913.

HENRY F. SCHMIDT.
